UNITED STATES PATENT OFFICE.

MATHEW G. DE WOLFF, OF TAMPICO, MEXICO.

SEALING DEVICE.

No. 845,619.

Specification of Letters Patent.

Patented Feb. 26, 1907.

Application filed January 24, 1906. Serial No. 297,697.

To all whom it may concern:

Be it known that I, MATHEW G. DE WOLFF, a citizen of the United States, residing at Tampico, in the county of Tampico, Republic of Mexico, have invented certain new and useful Improvements in Sealing Devices; and I do hereby declare the following to be a full, clear, and exact description of the invention, such as will enable others skilled in the art to which it appertains to make and use the same.

This invention relates to sealing devices and more particularly to that class of sealing devices used in applying sealing-wax to envelopes or the like.

The primary object of this invention is to provide a device of this character in which the wax is kept in liquid state and in which state it may be fed from the device to envelopes or the like.

A further object of the invention is to provide convenient means for regulating the feed of the sealing-wax.

In the accompanying drawings, Figure 1 is a side elevation of the invention. Fig. 2 is a vertical sectional view through the same. Fig. 3 is a top plan view of the invention, and Fig. 4 is a detail vertical transverse sectional view through the spout of the device.

Referring more specifically to the drawings, the numeral 5 denotes my sealing device comprising upper and lower members 6 and 7. The lower member 7 is in the form of a tank and is provided at its top with an outwardly-flaring annular flange 8, the said flange serving to hold the upper member 6 in proper relation with respect to the member 7. The member 7 is provided with a filling-spout 9, which is closed by means of a cap 10.

Centrally of its top the lower member 7 is provided with a wick-receiving tube 11, which extends above and below the top of said member 7. The portion of the tube 11 lying below the top of the member 7 is perforated, as at 12, to permit access of the fuel contained in the said tank to a wick 13 in the said tube. The upper member 6 of the sealing device is substantially cylindrical in form and includes a top 14 and a bottom 15,

which is disposed intermediate the top 14 and the lower edge of the said member. Extending centrally through the member 6 and having communication through the top 14 and the bottom 15 is a flue 16, which is provided at its upper end with a hinged closure 17.

The member 6 is provided adjacent its lower end with a series of draft-openings 18, and with an opening 19, through which a match may be inserted to light the wick 13. Disposed upon opposite sides of the openings 19 are vertical parallel guide members 20, between which is received a sliding closure 21, provided with a finger-piece 22. The member 6 is provided with a spout 23, which has its under side inclined downwardly and inwardly toward the said member, as shown at 24, and has its upper side lying in a plane above the bottom 15 of the said member and inclined downwardly and outwardly from the said member to its outer end, the said spout 23 having its top formed by bending its upper side edges inwardly toward each other. Communicating with the portion of the member 6 between the top 14 and the bottom 15 and disposed between the inwardly-directed flanges of the spout 23 is an outwardly-tapered spout 25. Pivoted between ears 26, formed on the upper face of the spout 25, is a lever 27, which is provided at its forward end with a plate 28, and which is bent rearwardly of its pivot-point to extend around the member 6, the extreme rear end of the said lever being provided with a finger-piece 29, which is so located that it may be readily reached from a handle 30, formed on the side of the member 6 opposite the side to which the spout 23 is attached.

In operation wax is placed in that portion of the member 6 between the top 14 and the bottom 15 and the wax melted by means of the lamp portion of the device. It will be seen that the passage of the heated air is through the flue 16 and the spout 23, the heated air passing through the flue 16 serving to melt the wax contained in the device and the air passing through the spout 23 serving to retain the molten wax in its liquid state until deposited upon an envelop or the like. It will be seen that pressure upon the finger-piece 29 of the lever 27 will serve to raise the plate 28 from the open end of the spout 25 to allow the wax to flow through the said spout, a leaf-spring 31 serving to return the lever to its normal position.

What is claimed is—

1. A device of the class described comprising a receptacle, a spout leading from one side of said receptacle, a heater arranged to heat said receptacle, and means for conducting the heat from said heater to said spout.
2. A device of the class described comprising

ing a receptacle, a spout leading from said receptacle, a flue located beneath said spout and partially inclosing the same, and a heater arranged to heat said receptacle and for the 5 passage of the heat through the flue.

3. A device of the class described comprising a receptacle, a spout having communication with said receptacle, a second spout arranged below said first-named spout and arranged for the passage of air therethrough, and means for heating said receptacle and said last-named spout. 10

4. A device of the class described comprising a receptacle, a spout leading from one

side of said receptacle, a handle located at 15 opposite sides of said receptacle, a lever pivoted to the spout and extending around said receptacle with one of its ends located adjacent said handle, said lever being provided at its operate end with a plate to close 20 said spout.

In testimony whereof I affix my signature in presence of two witnesses.

MATHEW G. DE WOLFF.
